UNITED STATES PATENT OFFICE.

JOHN C. OGDEN, OF WESTMONT BOROUGH, PENNSYLVANIA.

METHOD AND APPARATUS FOR MOLDING.

1,134,404.

Specification of Letters Patent.

Patented Apr. 6, 1915.

Application filed March 17, 1911. Serial No. 615,004.

To all whom it may concern:

Be it known that I, JOHN C. OGDEN, a citizen of the United States, residing in the borough of Westmont, in the county of Cambria and State of Pennsylvania, have invented certain new and useful Improvements in Methods and Apparatus for Molding; and I do hereby declare the following to be a full, clear, and exact description of 10 the invention, such as will enable others skilled in the art to which it appertains to make and use the same.

My invention relates to the method and apparatus for making sand molds or the 15 like, and more especially to the art of making metal ingot-molds to be used for casting ingots.

An object of my invention is to provide a method and means for making the molds 20 which are simple and efficient in operation and construction, and wherein the capacity of a mold foundry output is greatly increased.

Another object is to retain the molding 25 material within the flask while allowing a pattern-plunger of tapering form to reciprocate within the flask in order to compress the molding material simultaneously throughout the length of the mold and at 30 the same time force the lug patterns outwardly to form lug molds.

A further object is the manner in which I am enabled to cast in the staples on the 35 sides of the casting and also the manner and means of forming the runners or gits.

Other objects of the invention will appear hereinafter.

Molds for casting steel ingots are usually 40 made of cast iron, although sometimes other material is used. After these molds have been in use for a while the interior of the same becomes burned or rough, so that the ingot sticks, when cast, and has to be forced out of the mold. When this is the case, or 45 when it is cracked or otherwise defective, the mold has to be replaced by a new one.

My invention produces better molds thus 50 conducing to economy and ease of use.

To enable others skilled in the art to make 55 and use my invention, I will now describe the same more fully, referring, for that purpose, to the accompanying three sheets of drawings which form a part of this specification and in which—

Figure 1 is a vertical section of my im-

proved apparatus showing the parts in elevation, with the pattern-plunger in its lowered position. Fig. 2 is a vertical transverse section of the flask and the adjoining portions of the apparatus taken on the line 60 III—III of Fig. 4, showing the pattern-plunger in its second or intermediate position, the top end of the plunger being substantially flush with the cover of the flask and the sand or molding material having 65 been poured around the plunger. Fig. 3 is a vertical transverse section taken on the same line as Fig. 2, showing the pattern-plunger at the upper end of its stroke, with the molding material compressed thereby. 70 Fig. 4 is a vertical longitudinal section taken on the line IV—IV of Fig. 3. Fig. 5 is a vertical longitudinal section of a finished mold taken on the line V—V of Fig. 7, showing the same after the metal has been 75 cast therein. Fig. 6 is a front elevation of one side of the flask. Fig. 7 is a horizontal transverse section taken on the line 80 VII—VII of Fig. 5. Fig. 8 is a vertical section of a finished mold after the metal has been 85 poured therein, this view being taken on the line VIII—VIII of Fig. 7, showing the manner of casting an ingot mold with a partially closed end, by means of a cope. Fig. 9 is a top plan view of the 90 stripper plates and a portion of the floor within which they are adjusted and supported. Fig. 10 is a section taken on the line X—X of Fig. 9. Fig. 11 is a top plan view of the lug patterns. Fig. 12 is a vertical transverse section taken on the line 95 XII—XII of Fig. 11. Fig. 13 is a front elevation of the pattern face of one of the staple blocks; and Fig. 14 is a perspective view of one of the staple blocks.

Referring now to the reference numbers on the drawings:—1 indicates the foundation which may be built of concrete, masonry or other suitable material, having an 100 opening 2 in its lower portion for the reception of a hydraulic cylinder 3, provided with the ports 4 and 5. A groove or chase 6 at the side of the opening 2, receives pipe connections (not shown) to the ports 4 and 5, through which water or other fluid is supplied and discharged as desired, by means of a controlling valve. The hydraulic cylinder 3 is suspended from an annular bed casting 7 which rests upon a shelf 8 in the 105 foundation and is secured in place therein 110

by means of the anchor bolts 9 which are embedded in the foundation. A piston 10 is adapted to reciprocate within the hydraulic cylinder 3 and carries the piston-rod 11 which extends out beyond the usual gland at the head of the cylinder, and is there connected to my pattern-plunger 12. The foundation walls inclose a cylindrical chamber 13 in which the pattern-plunger 12 10 remains when in its lowered position. A plate 14, having a hole 15 in its center, forms a base for the flask and said plate is firmly secured over the upper end of the chamber 13 by means of the anchor rods 16, which 15 are connected at their lower ends to the tops of the anchor bolts 9 by sleeve nuts as shown, and said plate is supported by the sills 17.

A flask 18 made up of two parts of symmetrical construction, rests upon the plate 20 14 and is provided with a cover 19 hinged at 20 to a standard 21. The cover 19 has a perforation 22 in its center that registers with, but is smaller than, the hole 15 in the base plate 14 of the flask. At the forward 25 end of the cover 19 is a locking rod 23 mounted upon the base plate 14, and adapted to pass through a slot in the cover 19 and secure the same by means of a key 24.

In order to more easily swing the cover 30 open, before pouring in the molding material, or for removing the flask, an eye-bolt 25 is secured to the front edge of the cover to which a cable 26 is attached, extending thence over a pulley 27 down to a ring 28 35 at the top end of the piston-rod 29. The rod 29 is provided with a piston 30 which is adapted to reciprocate in a small hydraulic cylinder 31 mounted in an opening 32 in the foundation, and provided with 40 means (not shown) for supplying fluid thereto, and discharging same therefrom, thereby operating the piston as desired. This small hydraulic cylinder 31 has the usual stuffing box and gland and has a flange 45 33 around its upper edge with perforations therein, through which the anchor bolts 34 are secured, the lower ends of which are embedded in the foundation as shown.

In order to enable me to cast the ends of 50 the lifting staple 35 into the mold casting, I provide hand holes 36 in each half of the flask 18. A short neck 37 extends outwardly from these hand holes and a flange projects around the outer edge of the same as at 38. 55 A box-shaped member 39 fits within said hand-holes 36 having its inner side approximately flush with the inside of the flask, and a flange 40 extends around its outer edge, which registers with the flange 38 and 60 is clamped thereto by means of the horseshoe clamps 41, or by bolts, or in any other suitable manner.

My stripper plates 42 are made in sections 55 as shown to prevent the sand or molding material from escaping around the pattern-

plunger. These stripper plates rest and slide in a correspondingly shaped annular recess 43 in the flask floor plate 14, and have lugs 44 projecting from their lower sides, which are adapted to move in the 70 guideways 45 in the flask floor plate.

The flask 18 has an offset on each half, so that when the two sections of the flask are secured together a side channel is provided, in which I form the geat of the mold. 75

The numeral 46 indicates the geat which is made by means of a former. This former consists of a pear-shaped head 48 beveled around its lower edge and thereby adapted to be seated in the opening 49 of the base 80 plate 14 and pass up through the notch 50 in one of the stripper plates 42. This former 48 is mounted on the rod 47, the upper end of which latter is formed into an eye 51 through which any suitable means may be 85 attached when it is desired to draw the former through the molding material for the purpose of forming the geat 46. An opening 52 is provided in the cover of the flask, through which the rod 47 is drawn as desired. 90

53 indicates my lug patterns which are placed near the top of the flask, as shown in Fig. 2, and as the pattern-plunger is raised, the lugs are forced outwardly as indicated in Fig. 3. 95

After the mold is formed, the flask, with the contained mold, is raised from the base plate 14 and placed upon the casting base 54 as shown in Figs. 5 and 8. A core 55 100 having its molding surface composed of baked core sand containing binders, or composed of other suitable material, is placed within the center of the flask resting on the base casting. Staple blocks 56 having an annular recesses 57 to form bosses on the casting around the staple ends, are also composed of baked core sand, or other material, and these are placed in the hand holes 36 while the plate 58 retains them in position. 110 If it is desired to make a mold casting with a closed, or partly closed end, a cope 59 may be placed on top of the flask, as shown in Fig. 8. 115

The operation of my method and apparatus is as follows:—Assuming that the apparatus is in the position shown in Fig. 1, the pattern-plunger is then raised until its top is substantially flush with the flask cover 19; the key 24 is then removed from the locking-rod 23 and the flask cover is swung upwardly by means of the cable 26 and the small hydraulic cylinder 31, until it reaches a vertical position, as shown by the dotted lines. The space between the flask 18 and the pattern-plunger 12 and around the rod 47 is then filled with sand or other molding material about up to the level of the lower part of the lug patterns which are then placed by hand on either side of the pat. 125 130

tern-plunger, near the top of the flask; the filling of the flask with molding material is then completed and the flask cover is then lowered to the position shown in Fig. 2. 5 The pattern-plunger is then further raised by means of the hydraulic cylinder 3 until the piston 10 reaches the upper end of its stroke, and owing to the tapered form of the pattern-plunger, (the lower portion having 10 the greatest cross sectional area), the sand or molding material between the pattern-plunger and the walls of the flask is laterally compressed into the form as shown in Figs. 3 and 4 and at the same time the lug 15 patterns are laterally forced into the molding material, while the flask cover holds them from moving upward. I now pull out the gear former 48 which can be readily done, as the molding material will not have become 20 so thoroughly compressed in this offset channel portion as at other points within the flask, although it has been partially compressed by placing it around the rod 47, and further slightly compressed by the movement of the pattern-plunger 12. This withdrawal of the former 48 makes a smooth surfaced passage or gear by laterally compressing the molding material. The pattern-plunger is now withdrawn downwardly 25 and the lug patterns are taken out. The box-shaped members 39 which fit within the hand holes 36 are taken off and the molding material cut out to register with the sides of the hand holes. After this, the flask cover 30 is again raised, the flask with its contained molds is removed and the gear connected with the inside of the mold as at 60 which designates a sprue. A base plate 54, having its upper portion protected with molding 35 material, now receives a core 55, placed upon its center, then the flask with its mold is raised and seated upon the base plate 54 surrounding the core, leaving a space between the two for the mold casting. The 40 staple blocks 56 are now placed in the hand holes 36 with the ends of the staples extending into the space between the outside of the mold and the core, and a plate is clamped over the face of the hand hole for retaining 45 the blocks in place while pouring. The mold is now completed and is ready for pouring. When pouring, if desired, a refractory-lined funnel may be used as shown at 61, in which case, the metal, when poured 50 into it, will flow down through the passage or gear 46 and thence rise in the mold until it reaches the top of the same, thereby forming the mold casting as indicated by the numeral 62. As the metal shrinks or contracts while cooling, after the mold has been 55 filled, I pour a small quantity of metal around the top of the mold casting to compensate for the shrinkage.

I may wish to form a mold casting with a 60 closed, or partly closed top, as shown at 63

in Fig. 8, in which case I add a cope to the top of the flask, while otherwise the operation is the same.

Although I have shown and described my improvements in considerable detail, I do 70 not wish to be limited to the exact and specific details shown and described, but may use such substitutions, modifications or equivalents thereof, as are embraced within the scope of my invention, or as pointed out 75 in the claims.

Having thus described my invention, what I claim and desire to secure by Letters Patent is:

1. The method of forming molds, which 80 consists in placing molding material within a flask around the smaller end of a tapered pattern-plunger, then inserting further patterns around and in contact with the said pattern-plunger, and then moving said pattern-plunger longitudinally, thereby simultaneously compacting the molding material. 85

2. The method of forming molds, which 90 consists in placing molding material within a flask around the smaller end of a tapered pattern-plunger, then inserting lug patterns around and in contact with said plunger, then simultaneously compressing the molding material throughout its length by moving said plunger longitudinally, then forming 95 a gear in the molding material and then withdrawing the pattern-plunger from the mold.

3. The method of forming molds, which 100 consists in placing molding material within a flask around the smaller end of a tapered pattern-plunger, then inserting lug patterns around and in contact with said plunger, then simultaneously compressing the molding material throughout its length by moving 105 said plunger longitudinally, then forming a gear in the molding material by pulling a pear-shaped former therethrough, then withdrawing the pattern-plunger from the mold and setting inserts in the sides 110 of the mold.

4. The method of forming molds, which 115 consists in placing molding material within a flask around the smaller end of a tapering pattern-plunger, inserting lug patterns in contact with the said tapering pattern-plunger, simultaneously compressing the molding material throughout its length by moving said plunger longitudinally, forming 120 a gear in the molding material, withdrawing the tapering pattern-plunger from the mold, connecting the gear with the mold and setting inserts in the sides of the molds.

5. The method of forming molds, which 125 consists in placing molding material within a flask around the smaller end of a tapering pattern-plunger, inserting lug patterns in contact with the said tapering pattern-plunger, simultaneously compressing the molding material throughout its length by 130

the longitudinal movement of said plunger, forming a gear in the molding material, withdrawing the tapering pattern-plunger from the mold, connecting the gear with the mold, setting inserts in the sides of the molds and then placing the mold thus formed upon a casting base having a central core.

6. The method of forming molds, which 10 consists in placing molding material within a flask around the smaller end of a tapering pattern-plunger, inserting lug patterns in contact with the said tapering pattern-plunger, simultaneously compressing the molding material throughout its length by the longitudinal movement of said plunger, forming a gear in the molding material, withdrawing the tapering pattern-plunger from the mold, connecting the gear with the 15 mold, setting inserts in the sides of the molds, seating the mold thus formed upon a casting base having a central core, and placing a cope over the top of the mold.

7. The method of forming gears or runners 25 for molds, which consists in placing molding material around a rod or core, provided with a tapered head or enlargement, then slightly compressing the molding material, and then drawing said head through the molding material by means of said rod, thereby further 30 compressing said material and forming the gear.

8. The method of forming gears or runners for molds, which consists in placing 35 molding material around a rod or core, provided with a tapered head or enlargement, then slightly compressing the molding material, and then drawing said head through the molding material by means of said rod, thereby further 40 compressing said material and forming the gear, and then connecting said gear with the interior of said mold.

9. In a molding machine, comprising a flask, a tapered pattern-plunger extending 45 therein, molding material within the flask and surrounding the said tapered plunger, a secondary pattern placed within the flask and in contact with the said pattern-plunger, and means for advancing the said tapered 50 pattern-plunger to embed said secondary pattern and simultaneously compress the molding material throughout the length of the mold.

10. In a molding machine, comprising a 55 flask seated on a base plate and having a movable cover, a tapered pattern-plunger extending therein, molding material within the flask and surrounding the tapered pattern, lug patterns placed within the flask in contact with the tapered pattern-plunger and means for advancing the said tapered plunger to compress the molding material simultaneously throughout the mold between the tapered plunger and the flask.

65 11. In a molding machine, a flask seated

on a base plate and having a movable hinged cover, means for raising and lowering said movable hinged cover, a tapered pattern extending through the flask and surrounded with molding material and means for raising and lowering said tapered pattern to simultaneously and laterally compress all the 70 said molding material.

12. In a molding machine, a flask seated 75 on a base plate and having a movable hinged cover, means for raising, lowering and locking said movable hinged cover, a tapered pattern extending through the flask and surrounded with molding material, means for advancing the tapered pattern to laterally 80 compress all the said molding material simultaneously, and a stripper for preventing the molding material from escaping around the tapered pattern.

13. In a molding machine, a flask seated 85 on a base plate and having a movable cover, a reciprocable tapered pattern-plunger adapted to work within the flask, molding material surrounding said plunger, sectional stripper plates in approximate contact with 90 the pattern for retaining the molding material, and lugs on the stripper plates working in guideways in the base plate.

14. In a molding machine, a flask seated 95 on a base plate and having a movable cover, a reciprocable pattern-plunger within the flask, molding material surrounding said pattern-plunger, a stripper composed of a plurality of plates encircling the pattern for retaining the molding material and lugs on 100 the stripper plates working in guideways on the base plate.

15. In a molding machine, a flask having 105 a cover and base plate with openings therein, a tapered pattern-plunger therein surrounded with molding material and adapted to reciprocate within the flask and thereby laterally compact all said molding material, an offset channel in the side of the flask and a former for constructing a gear or runner in 110 the molding material within the offset channel portion, after the said molding material has been slightly compressed in said offset channel.

16. In a molding machine, comprising a 115 flask having a hinged cover and base plate with openings therein, a tapered pattern-plunger therein, surrounded with molding material and adapted to reciprocate within the flask, an offset channel in the side of the 120 flask and a former consisting of a rod having an elongated tapered head for constructing a runner in the molding material within the offset channel portion.

17. In a molding machine, a flask, a mold 125 contained therein, an offset channel in the side of said flask, and a former consisting of a rod having a pear-shaped head for constructing a runner in the molding material within the offset channel portion, after the 130

- said molding material has been slightly compressed in said offset channel.
18. In a molding machine, a flask, a mold contained therein, an offset channel in the side of said flask, a former consisting of a rod having a substantially pear-shaped head and normally seated in an opening in the flask base, molding material surrounding said rod, and means for drawing said rod and its attached head through said molding material, after the said molding material has been slightly compressed in said offset channel, whereby a gear or runner is formed therein.
19. In a molding machine, a flask, a mold contained therein, an offset channel in the side of said flask, a former consisting of a rod, within said offset channel, having a substantially pear-shaped head normally seated in an opening in the flask base and adapted to be drawn through the molding material surrounding the same, after the said molding material has been slightly compressed in said offset channel, to form a runner for the mold.
20. In a molding machine, a flask, a
- tapered pattern-plunger therein, molding material within the flask and surrounding said pattern-plunger, means for operating the plunger to simultaneously compress the molding material throughout the length of the flask, movable lug patterns placed on either side of the pattern and staple blocks inserted through hand holes in the flask and cutaway portions of the mold.
21. In a machine for making molds and cores for ingot molds, a pattern, a flask arranged in line therewith, means for retaining a body of mold forming material in the flask and means for advancing the pattern longitudinally into the flask to shape and compress the mold forming material therein, in combination with means for forming shoulder cavities in the formed mold to produce lifting lugs on the ingot mold when cast.

In testimony whereof I hereto affix my signature in the presence of two witnesses.

JOHN C. OGDEN.
